FOLDING SAWHORSE

Eduard H. J. Storek, Nashville, III.

Application January 4, 1951, Serial No. 204,379

5 Claims. (Cl. 304—5)

1

The present invention relates to improvements in saw horses and more particularly to saw horses having longitudinally extending rails and foldable legs secured thereto. The invention also relates to saw horses having means for longitudinally extending the same as well as means for providing a vertical extension to the supporting legs.

An object of the present invention is to provide a folding saw horse having a longitudinally extending supporting rail and legs secured to each end thereof with means for hingedly securing the legs to the supporting rail for pivoting movement towards each other and for positioning in juxtaposition to the supporting rail whereby the saw horse may be conveniently stored or transported.

A further object of the present invention is to provide a folding saw horse with means for releasably latching the hingedly secured legs in their supporting position relative to the supporting rail.

A still further object of the present invention is to provide a brace means for preventing movement of the legs with respect to the supporting rail when the latch means is in released position.

Another object of the present invention is to provide a saw horse having a pair of supporting rails, each of the supporting rails being provided with a pair of legs fixedly secured thereto, said supporting rails being adapted to be secured together to provide an elongated saw horse.

A further object of the present invention is to provide means for rigidifying the elongated saw horse by providing connecting struts between intermediate portions of the supporting rails and the lower end portions of the legs.

It is also an object of the present invention to provide a conventional saw horse with means for vertically extending the same with respect to a supporting surface, the means comprising extension legs securable to the lower ends of the legs of the conventional saw horse, joinder struts being provided for connecting the lower ends of the extension legs for rigidifying the entire structure.

Various other objects and advantages will become apparent from the detailed description to follow. The best forms in which I have contemplated employing my invention are clearly illustrated in the accompanying drawings, wherein:

Figure 1 is a side elevational view of a first form of folding saw horse;

2

Figure 2 is a top plan view of a portion of the saw horse of Figure 1;

Figure 3 is an end elevational view of the saw horse of Figure 1;

Figure 4 is a side elevational view of the folding saw horse in folded position;

Figure 5 is a longitudinal vertical sectional view taken substantially along the plane of line 5—5 of Figure 3;

Figure 6 is a vertical transverse sectional view taken substantially along the plane of line 6—6 of Figure 5;

Figure 6a is an enlarged view in perspective of the brace means;

Figure 7 is a side elevational view of a modified form of longitudinally extensible saw horse;

Figure 8 is a top plan view of the saw horse of Figure 7;

Figure 9 is a vertical transverse sectional view taken substantially along the plane of line 9—9 of Figure 7;

Figure 10 is an end elevational view of a third form of vertically extensible folding saw horse; and

Figure 11 is a detail perspective view of the connecting bracket employed in the third form of the invention for receiving the lower ends of the legs of the conventional saw horse.

Referring more particularly to the drawings, 30 wherein like numerals designate like parts throughout, numeral 10 designates generally a first form of folding saw horse, the numeral 12 designates generally the elongated saw horse construction while the numeral 14 designates generally the vertical extension means for a conventional saw horse.

The folding saw horse construction 10 shown in Figures 1 through 6 is comprised of a first hinge bracket 16, latch elements 18 and 20, and 40 brace means 22.

The hinge bracket 16 is comprised of a first portion 24 which is fixedly secured to the supporting rail 26 by means of the bolts 28. The first portion 24 is of U-shaped cross-section with the upstanding walls 30 in abutment with the side walls of the supporting rail 26. The first portion 24 has a second portion 32 secured thereto, the second portion 32 being formed from angulated sheet metal section 34 providing 50 sockets for receiving the upper ends 36 of the legs 38. The second portions 32 are also formed with latch elements 40 which are comprised of portions of the plate 34 being slit and bent to provide an offset latching means.

55 A third portion 42 of the first bracket 16 is

hingedly connected to the first portion 16 by means of the hinge 44 and has a pair of hinge sections 46 and 48 hingedly secured thereto by the longitudinally extending hinges 50 and 52. The hinge sections 46 and 48 are comprised of angulated sheet metal strips which encircle three sides of the legs and are secured to the inner and outer surfaces of the legs by means of the bolts 54.

The longitudinally extending supporting rail 26 has a pair of latch elements 56 and 58 pivotally secured thereto by means of the bolt 60 and wing nut 62. The latch elements 56 and 58 are formed with offset portions 64 and 66 which are disposed in parallel relation to the side walls of the rail 26 and are adapted to be engageable over the offset portions 34. The latches 56 and 58 are formed with detent slots 65 for engagement with the detents 40 whereby when the upper ends 36 of the legs 38 are engaged underneath the offset portions 34, 64 and 66, the latching elements 56 and 58 will fixedly maintain the entire saw horse in its supporting relation.

Reciprocably received on the underside of the hinged portion 42 is the brace means 22 having the form of a plate longitudinally and slidably fitted between and supported by the hinges 50, 52 and which has a pair of angulated depending rear end portions 68, and a depending front lip 69 notched as at 69' to play between said hinges 50, 52. The brace means 22 is slideable forwardly to interpose the angulated portions 68 between the hinge sections 46, 48, as best shown in Figure 5, to maintain the legs 38 swung away from each other. The lip 69 engages the hinge 44 to limit forward sliding of said brace means. The brace means 22 may be slid rearwardly to withdraw said portions 68 from between the sections 46, 48, as shown in dotted lines in Figure 5, so that said sections 46, 48 may be swung toward each other and the legs 38 correspondingly swung. A depending stop element 72 on the hinge plate 42 extending into a slot 70 in said brace means 22 limits rearward sliding of said brace means.

An elongated rotatable element 74 is secured to the underside of the rail 26 by means of the screw 76 whereby when the element 74 is longitudinally disposed relative to the rail 26, the end 78 will be engageable with the brace means 22 for preventing outward movement thereof. The element 74 may be rotated to a transversely extending position to permit the retraction of the brace means 22 when it is desired to fold the saw horse.

From the foregoing, the manner in which the saw horse is folded will be readily understood by one skilled in the art. First, the element 74 is rotated to a transversely extending position and the brace means 22 is slid into its rearward limit of movement. The latch elements 56 and 58 are pivoted upwardly upon loosening of the wing nut 62, whereupon the legs 38 may be hingedly moved towards each other about the hinges 50 and 52 and also hingedly moved to a longitudinally extending position about the hinge 44. A conventional hook 80 and eyelet 82 are secured to the rail 26 and leg 38 respectively for latchably retaining the legs in folded position.

As seen in Figure 2, the latch elements 18 and 20 are formed with laterally extending finger engaging portions 84 and 86 and rigidifying plates 88 and 90. The latching elements may be pivoted about their pivotal axis by engaging the finger engaging portions 84 and 86. The angulated por-

tions 64 and 66 of the latch elements 18 and 20 are substantially rigidified by the plates 88 and 90.

Looking now at Figures 7 and 8, the elongated saw horse construction will be seen to comprise a pair of rails 92 and 94 having pairs of legs 96 angularly extending therefrom at their outer ends. Each of the rails 92 and 94 has a bracket 98 or 100 secured thereto. The brackets 98 and 100 are of rectangular cross-section and are secured to their respective rails 92 and 94 by means of the bolts 102. The internal cross-sectional area of the brackets 98 and 100 is sufficient to receive the two longitudinally extending rails 92 and 94.

Each of the rails 92 and 94 has a plate 104 or 106 secured thereto by means of the bolts 108. The plates 104 and 106 have arcuated portions 110 formed with transversely extending slots 112.

Each of the rails 92 or 94 has a pair of rigidifying rods 114 and 115 for interconnecting the rails to the legs 96. The rods 114 have connecting brackets 116 formed on their upper ends, the brackets 116 having arcuated end portions 118 positionable through the slots 112 for engagement over the arcuated ends 110 of the plates 104. The opposite ends of the rods 114 have elongated brackets 120 secured thereto and formed with longitudinally extending slots 122. The legs 96 are formed with rotatable latch elements 124 receivable through the slots 122 for releasably securing the rigidifying rods 114 and 115 to the lower ends of the legs 96.

To further rigidify the elongated saw horse construction, a fifth leg is provided. As seen in Figures 7 and 9, the fifth leg 126 is comprised of an elongated rectangularly cross-sectioned element 128 having a reduced upper end portion 130 extending therefrom. A pair of plates 132 and 134 are secured around the reduced portion 130 by means of the screws 136 and have their upper ends laterally extending at 138 and 140. A pivot plate 142 is pivotally secured to the laterally extending portion 140 by means of the pin 144 and has a downwardly angulated end 146 engageable over the laterally extending portion 138 whereby when the rail 92 is disposed in the space between the plates 132 and 134, the plate 142 will retain the leg 126 in supporting relation thereto.

Looking now at Figures 10 and 11, the vertically extensible folding saw horse construction will be described. A conventional saw horse 11 having a longitudinally extending supporting rail and angularly extending legs 150 has vertical extension means 14 secured to the lower ends of the legs 150 for maintaining the saw horse in raised relation to the supporting surface S.

The extension means 14 is comprised of an extension leg 152 for each of the legs 150, each of the extension legs 152 being provided with a connecting bracket 154. The connecting bracket 154 has an attaching portion 156 for securing the same to the extension leg 152, a rectangularly cross-sectioned portion 158 for slidably receiving the intermediate portion of the leg 150 and a socket portion 160 for receiving the lower end of the leg 150. The upper end of the extension leg 152 is provided with a conventional hook 162 for association with the eyelet 164 secured to the leg 150 for retaining the conventional saw horse 11 connected to the extension means 14.

Joiner struts 166 have connecting brackets 168 and 170 secured to their outer ends and 75 formed with elongated slots 172 and 174. The

extension legs 152 have rotatable elements 124 secured thereto for positioning through the slots 172 and 174 for fixedly retaining the legs 152 and joinder struts 163 together.

Having described the invention, what is claimed as new is:

1. In a saw horse, including a longitudinal rail and a pair of legs at opposite sides of the rail, means for attaching the legs to said rail for folding under the rail comprising a U-shaped bracket straddling the bottom of the rail and having angulated sockets integral therewith and straddling the legs at corresponding sides of said legs, a plate portion on said bracket beneath the rail hinged to said bracket for swinging about an axis transverse to the rail to fold the legs under the rail, a pair of angulated sections straddling the legs at the sides thereof opposite the first-mentioned sides and having hinges connecting the same to said plate portion for swinging about parallel axes extending longitudinally of said rail for swinging of said angulated sections on said plate portion to swing the legs toward and from each other, coacting latch means on said rail and sockets for locking said plate portion against swinging to fold said legs, and a member slidably between said angulated members for preventing swinging of the same to swing the legs toward each other.

2. In a saw horse according to claim 1, said coacting latch means comprising latch portions on said sockets, and pivoted latch elements on said rail formed with offset portions for straddling said sockets and having slots therein engageable with said latch portions.

3. In a saw horse according to claim 1, said angulated sections straddling the legs below said sockets.

4. In a saw horse according to claim 1, said member being slidably supported between and by said hinges.

5. In a saw horse according to claim 1, said member comprising depending angulated portions engageable with said angulated sections.

EDUARD H. J. STORCK.
